FILLING FORK

James M. Tuten, Greenville, S. C., assignor to
Draper Corporation, Hopedale, Mass., a corpora-
tion of Maine

Application July 18, 1952, Serial No. 299,655

9 Claims. (Cl. 139—377)

1

This invention pertains to filling forks for looms such as are adapted to sense the presence or absence of filling at some point along a loom lay and to serve in initiating a stopping action through the conventional stop motion of the loom.

It is a general object of the invention to provide a filling fork of the type described which shall present certain safety features, e. g., which shall provide for engagement of the fork prongs with a shuttle or other obstruction without damage to the fork, and which will also return to its normal operative position or relationship after the fork prongs have become disengaged from the obstruction.

Other objects of the invention will become apparent from the following more detailed description.

In looms for weaving the filling is periodically contacted by certain stop motion devices including a filling fork which cooperates with a grid to sense the presence or absence of filling so as to stop the loom in the event that filling is not present as intended. These fork devices normally comprise a holder from which project one or more prongs adapted to cooperate with the grid and also a loop or similar part adapted to be engaged by a filling motion hook which is periodically actuated, but which has no effect except at such times as an indication of filling failure has been taken.

If loom operation does not deviate from that intended, the filling fork prongs never encounter anything except the filling itself and thus there is no interference and the parts may be made relatively light in weight and need not have more than reasonable strength. Lightness of these parts is to be desired since the filling is relatively weak in many instances and the fork parts should present very little mass so that their resistance to movement and their inertia shall be relatively negligible. However, in certain instances, either due to errors on the part of the weaver or due to mechanical difficulties attendant upon the loom structure or operation itself, the shuttle is sometimes stopped and left at a point along the lay such that the filling fork prongs engage it either as the lay is moved forwardly or rearwardly and several expedients have been adopted at times in an effort to prevent damage to the fork members when that occurs. Frequently the fork tines or prongs have been made flexible so that they may bend out of the way and then return to their normal position, and in one instance at least, as evidenced in United States Patent No. 1,372,084, the fork prongs have been sprung urged in one direction against a stop so that they may spring out of the way if they encounter a trapped or

misplaced shuttle. The mechanism of this patent functions only if the shuttle is engaged by movement of the lay in one direction, that is forwardly, while the flexible prongs are open to the objection that they tend to vibrate if they are made sufficiently elastic so that they may be sprung out of the way yet return to their original position, or in some instances, become slightly bent and therefore do not perform the filling function properly.

According to the instant invention, a very simple and compact filling fork has been devised which employs relatively inflexible or rigid prongs of normal size and construction and which may, upon engagement with a misplaced shuttle or other obstruction, move past that shuttle or out of the way without damage to any of the parts and will do that no matter which direction the shuttle moves toward the prongs. The fork is also so devised that after having passed the obstruction, the prongs return to their original or normal position so that it is not necessary for the weaver to perform that function manually.

The invention will be described in greater detail by reference to one particular embodiment thereof as illustrated in the accompanying figures of drawing wherein:

Fig. 1 is a perspective view showing the novel filling fork applied to a typical fly shuttle loom.

Fig. 2 is a section taken through the novel filling fork showing the details of the construction thereof.

Fig. 3 is a section through the lay and attendant parts of a loom showing the relative relationship of the filling fork thereto.

Fig. 4 is a view showing the fork when the prongs thereof have been engaged and displaced due to movement of the lay forwardly when the shuttle has been mispositioned so as to present an obstruction in the pathway of the filling fork prongs.

Figs. 5 and 6 are similar sectional views but showing the manner in which the filling fork functions upon engagement of the prongs at the opposite side of a mispositioned shuttle.

Now referring to Fig. 1, enough of a conventional loom has been illustrated to show the relationship of the invention thereto. These looms comprise, among other parts, a reciprocable lay beam 10, along the shuttle race 11 of which a shuttle 12 is adapted to move as it is picked to and fro through a shed formed from warp threads 13 converging toward the fell of a fabric F which is woven and taken up in a conventional manner. These warp threads pass through a reed 14 held at its upper edge adjacent a hand rail 15, the lay mechanism being positioned at

3

the upper ends of a plurality of swords one of which is shown at 16 and which are oscillated to and fro in a manner well known to those conversant in this art. The shuttle is arrested and positioned at the outermost points of its travel at each end of the lay by shuttle box mechanism generally indicated by numeral 17 and which need not be described in detail here.

At at least one end of the lay beyond the reed, and possibly at both ends, there is provided a grid 18 which is adapted to cooperate with a filling fork having one or more, but preferably a plurality, of fork tines or prongs 19 held within a holder generally indicated by numeral 20 and which is pivoted at 21 adjacent the end of a filling fork slide 22, this slide extending forwardly and having cooperation with certain other stop motion mechanism well known to those skilled in the art and which will not be shown or described here. More or less horizontally disposed and projecting forwardly from the filling fork holder 20 is a loop 23 adapted to be engaged by a filling motion hook 24 which is periodically reciprocated throughout a slight angular extent by filling cam means of known construction. This hook normally fails to engage the loop 23 since the latter will have been raised as the fork is tilted about pivot 21 whenever the prongs 19 engage filling held in their pathway and positioned by the forward, vertical members of the grid 18. At such times as the filling is not present, or is not properly present since it is perhaps very slack, the filling fork will not be moved about its pivot and the loop 23 will then be in a position to be engaged by the hook 24 and stopping of the loom is thereby initiated since the hook 24 in moving forwardly will also move the filling fork slide 22 forwardly a corresponding amount, the other parts (not shown) thereafter functioning in the intended sequence to bring about the actual stopping of the weaving mechanism.

Now referring to Figs. 1 and 2, the filling fork holder generally indicated by numeral 20 is actually a two-part mechanism, one part 25 being slotted or notched as at 26 for the reception of an inner part 27, the loop 23 being fixed in the former while the prong or prongs 19 are fixed in the latter. These parts are normally, as will hereinafter be described, maintained in a definite position at which the loop 23 and prongs 19 are held more or less at right angles except as the prongs are engaged by an obstruction. A pivot 21 in the form of a tube or sleeve 28 passes through the forked ends of the part 25 and also through the part 27 so that the latter may pivot relatively to the former when the occasion arises. The pivot pin 21 on which the entire fork swings passes through this sleeve. A central, angularly disposed plunger retaining boss 29 is preferably cast integrally with the part 25 and is bored as illustrated in Fig. 2 at 29' so as to guide the plunger 30 having a stem 31 which is also guided in a smaller aperture at the upper or forward end thereof. A spring 31' normally tends to urge this plunger so that its point 32 is pressed against a cam surface on the adjacent face of the pivoted part 27. This cam surface actually comprises a central notch 33 and, at either side thereof, rounded lobes 34 and 35. When the plunger is engaged in the notch, as illustrated in this Fig. 2, the prongs are retained in a desired operative position. Under those conditions they function whenever they engage the filling relatively taut in front of the grid 18 and tilt the entire filling fork as intended so that hook 24 may not make

4

contact with loop 23. However, it does not require a great deal of force at the prongs to move the holder part 27 so that the parts may be moved as illustrated in Figs. 4 and 6 to clear an obstacle such as a shuttle, the plunger at that time being slightly displaced against the tension of spring 31'. The curvature of the cam lobes 34 and 35 is such that the spring and plunger will, when the prongs no longer are engaged by such an obstruction, automatically return the parts to their initial or normal position wherein the point 32 engages within the notch 33. It is obvious that the forces required to displace the prongs and part 27 may be varied by varying the contour of the cams and that in accordance with other practical requirements, the actual details of the parts may be varied within limits.

Now referring to Figs. 3 and 4, the shuttle 12 may be misplaced into the pathway of the fork 20 and when the lay is then moved forwardly as shown in Fig. 4, the prongs contact against the shuttle moving the part 27 about pivot 28. The plunger is pushed inwardly of its guiding bore against the tension of spring 31; but upon release, 25 the parts will be moved to original position ready for further operation of the loom. It is to be noted that the hand rail 15 is notched so that the filling fork may tilt without being obstructed. The function herein described and claimed is of 30 advantage when the loop 23 is caught by hook 24 when the parts are moving as in this Fig. 4.

The loom shuttle may be misplaced as indicated due to a human error, for example, when working on the loom, it is sometimes necessary to move 35 the shuttle from the box manually and if the loom is attempted to be started then, or if the lay is moved forwardly by hand wheel operation of the parts, the particular contingency just above described and illustrated in Figs. 3 and 4 is likely 40 to be encountered. At other times the parts may be in the position of Fig. 5 and the shuttle either moved manually so that it forms an obstruction in the path of the fork prongs when the lay is again moved to the rear, or this may occur under 45 power, for example, when a check strap becomes broken the shuttle rebounds excessively. That may happen at a time such as to present one of the situations herein given by way of illustration.

As shown in Fig. 6, the rearward movement of the lay parts swings the prongs and the holder member 27 in the direction reversely to that shown in Fig. 4 so that no damage is done and likewise, upon release of the prongs from the shuttle, the spring, plunger and appropriate cam lobe cooperate to return the parts automatically 55 to their normal and operative positions.

While one embodiment of the invention has been disclosed, it is to be understood that the inventive concept may be carried out in a number of ways. The invention is, therefore, not to be limited to the precise details described, but is intended to embrace all variations and modifications thereof falling within the spirit of the invention and the scope of the claims.

I claim:

1. A filling fork for looms which comprises a holder adapted to be pivotally mounted in a filling fork slide, a loop for engaging a filling motion hook and at least one filling engaging prong, said holder being comprised of two parts, 70 in one of which said loop is fixed and in the other of which the prong is held, and means normally effective for retaining said holder part in which the prong is held in fixed relationship to 75 the holder part in which the loop is fixed, but

operable upon engagement of the prong with an obstruction other than the filling for permitting a limited angular movement of the prong and holder part in either direction independently of the part in which the loop is fixed so that the prong may move past the obstruction without damage.

2. A filling fork for looms which comprises a holder adapted to be pivotally mounted in a filling fork slide, a loop for engaging a filling motion hook and at least one filling engaging prong, said holder being comprised of two parts, in one of which said loop is fixed and in the other of which the prong is held, and means normally effective for retaining said holder part in which the prong is held in fixed relationship to the holder part in which the loop is fixed, but operable upon engagement of the prong with an obstruction other than the filling for permitting a limited angular movement of the prong and holder part in either direction independently of the part in which the loop is fixed so that the prong may move past the obstruction without damage, said means further serving to return the prong and holder part to normal position after release.

3. A filling fork for looms which comprises a holder adapted to be pivotally mounted in a filling fork slide, a loop for engaging a filling motion hook and at least one filling engaging prong, said holder being comprised of two parts, in one of which said loop is fixed and in the other of which the prong is held, and means including a cam forming a surface of one part and a spring pressed cam engaging member on the other for retaining said holder part in which the prong is held in fixed relationship to the holder part in which the loop is fixed, but effective to permit the prong and its holding part to be displaced.

4. A filling fork for looms which comprises a holder adapted to be pivotally mounted in a filling fork slide, a loop for engaging a filling motion hook and at least one filling engaging prong, said holder being comprised of two parts, in one of which said loop is fixed and in the other of which the prong is held, and means including a cam forming a surface of one part and a spring pressed cam engaging member on the other for retaining said holder part in which the prong is held in fixed relationship to the holder part in which the loop is fixed, but effective to permit the prong and its holding part to be displaced, said cam and spring pressed cam engaging member further being effective, when the prong is released, to return the parts to their normal position.

5. A filling fork for looms which comprises a holder adapted to be pivotally mounted in a filling fork slide, a loop for engaging a filling motion hook and at least one filling engaging prong, said holder comprising a slotted part to which the loop is fixed and a second part pivoted to the first within the slot therein and by which said prong

is held, and means including a cam forming a surface of one part and a spring pressed cam engaging member on the other for retaining said holder part in which the prong is held in fixed relationship to the holder part in which the loop is fixed, but effective to permit the prong and its holding part to be displaced.

6. A filling fork for looms which comprises a holder adapted to be pivotally mounted in a filling fork slide, a loop for engaging a filling motion hook and at least one filling engaging prong, said holder being comprised of two parts, in one of which said loop is fixed and in the other of which the prong is held, means by which the second mentioned part is pivotally mounted in the first, a cam formed as a part of the second mentioned part, and a spring pressed plunger mounted in the first mentioned part and engageable with the cam for retaining said holder part and prong in fixed relationship to the part in which the loop is fixed, but effective to permit the prong and its holding part to be displaced, and further to return the parts to their normal operating position when the prong is released.

25 7. A mechanism as in claim 6 wherein said cam comprises a centrally disposed notch and substantially symmetrical cam lobes at each side of said notch.

30 8. A filling fork for looms which comprises a holder adapted to be pivotally mounted in a filling fork slide, a loop for engaging a filling motion hook and a plurality of filling engaging prongs, said holder being comprised of two parts one of which is pivoted for a limited swinging movement in the other, said loop being fixed in one holder part and said prongs being held by the other, and means for normally retaining said holder parts in a position in which the loop and prongs are substantially at right angles and for permitting the pivoted part of the holder and prongs therein to be displaced angularly to clear an obstruction which comprises a cam surface on that part in which said prongs are held and a spring pressed means forming a part of the other holder part said cam surface including two lobes at either side of a centrally disposed notch.

35 9. Mechanism as defined in claim 8 wherein said spring pressed member includes a plunger, guide means forming a part of the holder in which said plunger is movable and a spring housed in said guide means and urging said plunger into contact with the cam.
